UNITED STATES PATENT OFFICE.

PETER H. JACKSON, OF SAN FRANCISCO, CALIFORNIA.

GIRDER AND BEAM.

SPECIFICATION forming part of Letters Patent No. 279,249, dated June 12, 1883.

Application filed June 3, 1882. (No model.)

To all whom it may concern:

Be it known that I, PETER H. JACKSON, of the city and county of San Francisco, State of California, have invented an Improvement in 5 Girders and Beams; and I hereby declare the following to be a full, clear, and exact description thereof.

My invention relates to certain improvements in supporting girders and beams, and 10 in a means for uniting the ends of what are known as "trimmer-beams," which may abut against the sides of those known as "header-beams" or "girders," when the latter are composed of two or more beams, so as to keep both 15 at the same level, and form a strong and at the same time adjustable union between them.

It consists of a shoe having tongues projecting so as to fit above and below the header-beams, and having a suitable socket in one side, into 20 which the end of the trimmer-beam fits and is bolted. By making tongues on the top and bottom to fit all the beams composing the header, in case they do not fit, or by wedging them, so as to equalize the pressure, the weight 25 of the trimmers is distributed on all the beams, as will be more fully explained by reference to the accompanying drawings, in which—

Figure 1 is a perspective view. Fig. 2 is a transverse section. Fig. 3 is a view of the di 30 aaphragm. Fig. 4 shows manner of connecting the ends. Fig. 5 is a modification.

In many places, in the construction of buildings, and particularly in the laying of the beams to support the sidewalks in basement-exten 35 sions, it is necessary to connect these beams, which are called "trimmers," with the sides of other beams, called "headers," running at right angles with them. These beams are of iron, usually of an I section, and they are 40 ordinarily secured by straps of iron bolted to them. In order to strengthen the header-beams without increasing their size or depth, I have laid two or more side by side. The trimmer-beams are then made to abut against 45 the outside one, and if secured in the ordinary manner the whole weight and strain would fall upon the outer header-beam. In order to provide a convenient connection for the trimmer and header beams, and also a means for dis-

tributing and equalizing the weight, I construct 50 a shoe, A, having an opening formed in one side to receive the end of the trimmer-beam B. The opposite side of the shoe is formed to fit the side of the header-beam C, and has tongues D E, which extend across the top and bottom 55 of the header-beams C C, as shown. When two or more beams C are to be placed side by side, I fit a diaphragm, F, between them, having the shape of the space between the beams, where it fits perfectly, and is bolted in 60 place. At the junction where the ends of two beams abut these diaphragms extend a short distance into each one. Any weight or strain, therefore, which is brought upon one of the beams C will be transmitted to the other, and 65 the two will act as one. As the weight of the trimmer-beams is all applied to one side of the outer header-beam, I transfer it to the inner ones and equalize the pressure upon all the beams by causing the tongues to press 70 equally upon all the beams.

In some cases a single tongue extends across the tops of the beams C; but where there are a number of these beams I prefer to extend a tongue above and below, and they may be 75 united at the inner ends by vertical bolts H, which makes the tongues act in concert. By this construction the trimmer-beams are easily 80 united to the headers. The strength of the latter may be multiplied indefinitely by placing a number side by side and bolting diaphragms F between them, and the weight of the trimmers may be distributed between them all by the tongues and bolts.

Having thus described my invention, what I 85 claim as new, and desire to secure by Letters Patent, is—

1. The parallel beams C C and the abutting beam B, in combination with the intervening shoe, A, having one side recessed to receive 90 the end of the beam B, and having the tongue D projecting from and on top of the beams C, substantially as and for the purpose herein described.

2. The parallel beams C C and the abutting beam B, in combination with the intervening shoe, A, having the tongues D E projecting from the opposite side above and below the

beams C, and bolted together, substantially as and for the purpose herein described.

3. The parallel beams C C and the abutting beam B, with the intervening shoe, A, having one side recessed to receive the end of the beam B, and the tongue or tongues D E, as shown, in combination with the interior diaphragm, F, fitting closely between the parallel beams C

C, to form with the tongues both an internal and external support, herein described. 10

In witness whereof I hereunto put my hand.

PETER H. JACKSON.
